DESIGN FOR A WIND REED MUSICAL TOY OR THE LIKE

Harry Pullen, Preston, Md.

Application April 29, 1936, Serial No. 62,377

Term of patent 3½ years

To all whom it may concern:

Be it known that I, Harry Pullen, a subject of the King of Great Britain, residing at Preston, in the county of Caroline and State of Maryland, have invented a new, original, and ornamental Design for a Wind Reed Musical Toy or the like, of which the following is a specification, reference being had to the accompanying drawing forming part thereof, and in which:

Fig. 2 is a view similar to Figure 1 taken from a different angle.

I claim:

The ornamental design for a wind reed musical toy or the like, as shown.

HARRY PULLEN.
